LACE

Rena Silber, Sunnyside, N. Y., assignor to Native Laces & Textiles, Incorporated, New York, N. Y., a corporation of New York

Application January 22, 1958, Serial No. 49,357

Term of patent 14 years

(Cl. D47—6)

The figure on the drawing is a plan view of a lace showing my new design on a dark background so as to bring out more clearly the details thereof, a unit of which is repeated lengthwise between the selvage edges of the fabric as shown.

I claim:

The ornamental design for a lace, substantially as shown and described.
